UNITED STATES PATENT OFFICE.

EPPA H. RYON, OF WALTHAM, MASSACHUSETTS, ASSIGNOR TO CROMPTON & KNOWLES
LOOM WORKS, A CORPORATION OF MASSACHUSETTS.

SHEDDING MECHANISM FOR LOOMS.

1,068,822.

Specification of Letters Patent.

Patented July 29, 1913.

Application filed July 25, 1912. Serial No. 711,392.

To all whom it may concern:

Be it known that I, EPPA H. RYON, a citizen of the United States, residing at Waltham, in the county of Middlesex and State of Massachusetts, have invented certain new and useful Improvements in Shedding Mechanism for Looms, of which the following is a specification.

My invention relates to shedding mechanism for looms, and more particularly to a "dobby" so-termed, and the object of my invention is to improve upon the construction of the dobby shown and described in U. S. Letters Patent, No. 884,613, dated April 14, 1908.

My invention consists in certain novel features of construction of my improvements as will be hereinafter fully described.

The dobby of the type referred to is provided with a vertically extending rock shaft at each end of the dobby frame, said rock shafts are adapted to operate the lifter bars or reciprocating knives. A rocking or reciprocating rotary motion is communicated to said rock shafts from a horizontally extending transverse shaft, having bevel gear segments thereon, on each end thereof, which mesh with and operate bevel gears fast on the upper ends of the vertically extending rock shafts.

In my improved construction of a dobby, I do away with the horizontally extending transverse shaft, having two bevel gear segments thereon, and have one bevel gear segment, preferably located at the rear of the dobby frame, which bevel gear segment is in mesh with and operates a bevel gear on one of the vertically extending rock shafts at the rear of the dobby, said vertically extending rock shaft is provided with two crank arms, which are suitably connected to the lifter bars on one end thereof. The other ends of the lifter bars or reciprocating knives are pivotally mounted on a stand which is secured to the front dobby frame, and extends outwardly therefrom.

It will be seen that the movement of the lifter bars at the front of the dobby is less than the movement of the lifter bars at the rear of the dobby, which causes the harnesses to be lifted higher from the front to the back, corresponding with the angle of the shed desired.

Through the operation of the vertical

rock shaft a simultaneous movement is imparted to the reciprocating knives or lifter bars, which in this instance is unequal in extent in comparison to the more or less throw of the harnesses, in the rear, and in front of the loom. I also provide improved dobby fingers or levers, each one of which is adapted to operate in unison the upper and lower hooks, and which have in this instance two different or double runs for the pattern indication. By this means a "double index" chain may be used, the chain cylinder being timed to bring one set of indicator pegs under one set of runs for one pick, and the other set of indicator pegs for the other set of runs for the next pick.

The dobby may be changed to single index by simply changing the indicator fingers, and the time of the pattern cylinder, so that a new chain bar is brought under the indicator levers for each pick.

I have only shown in the drawings a detached portion of a dobby of the type above referred to, with my improvements combined therewith, sufficient to enable those skilled in the art to understand the construction and operation thereof.

Referring to the drawings:—Figure 1 is a rear elevation of portions of a dobby of the type above referred to, with my improvements applied thereto. Fig. 2 is a section, on line 2, 2, Fig. 1, looking in the direction of arrow *a*, same figure, and showing the driving mechanism of the vertically extending rock shaft. Fig. 3 is a plan view and section, on line 3, 3, Fig. 1, looking in the direction of arrow *b*, same figure. Fig. 4 corresponds to Fig. 3, but shows the lifter bars in their opposite position. Fig. 5 is a section, on line 5, 5, Fig. 3, looking in the direction of arrow *c*, same figure, and showing the harness jack or lever, and hooks, and other parts, detached. Fig. 6 shows, on an enlarged scale, a side view of a dobby finger detached, and, Fig. 7 is an edge view of the dobby finger shown in Fig. 6, looking in the direction of arrow *d*, same figure.

In the accompanying drawings, 1 is the rear dobby frame or side, which, in connection with the frame 2 at the front, see Figs. 3 and 4, is adapted to support the several parts of the dobby, in the usual way. 3 is a worm gear on the end of the shaft 4, which meshes with and is driven by a worm 5 fast

on the rotary shaft 6, which turns in bearings 7. The bevel gear 8 is fast on the opposite end of the shaft 6, and meshes with and is driven by a bevel gear 9 fast on the 5 upper end of the upright shaft 10, which is supported at its upper end in a bearing 10', and has a rotary movement communicated thereto from some driven part of the loom, not shown.

10 The shaft 4, see Fig. 5, has mounted thereon the pattern chain cylinder 11, which carries the pattern chain 12, made up of bars linked together, and provided with pins or pegs 13, to engage or move the indicator fingers or levers 14, in the usual way. The indicator fingers or levers 14 are pivotally supported on the transverse rod 15, see Fig. 5, to extend over the pattern chain cylinder 11 at their outer ends, in the usual 15 way. At their inner ends the pattern indicator fingers are provided in this instance with two arms 14^a, and 14^b, which are offset relative to each other, as shown in Fig. 7. The lower arm 14^a has a recess 14^{a'} therein, 20 see Fig. 6, to receive the lower end of an upright wire 16, see Fig. 5, which extends under and engages an upper hook 17. The inner end of the arm 14^b has an upper projection 14^{b'} thereon, see Fig. 6, which extends under and engages directly with the lower hook 18, see Fig. 5. The upper set 25 of hooks 17 are moved longitudinally by a horizontally moving lifter bar or knife 19, and the lower set of hooks are moved longitudinally by a horizontally moving lifter bar or knife 20. The lower hook 18 is pivotally attached at its inner end to the lower end of a harness lever 21, at its lower fulcrum point, which consists of a transverse 30 angle shaped bar 22, forming a part of and secured to the dobby frames 1 and 2, and having outwardly extending projections 22' thereon, which act as a comb for guiding and keeping in proper position the lower ends of 35 the harness levers 21, which have the downwardly extending projections 21' thereon, which extend between said projections 22', see Fig. 5. The other fulcrum point for the harness levers 21 is located intermediate 40 the ends of the harness levers 21, and consists in this instance of a transverse bar 23, see Fig. 5, which is secured to the front and rear frames 1 and 2 of the dobby; each harness lever 21 has an open end slot or 45 recess 21'' on its inner edge, to receive the transverse bar 23, which extends through said recess 21''. Near the inner end of the recessed portion 21'' is pivotally attached to the harness lever 21, the inner end of the 50 upper hook 17, which is adapted to be operated by the upper lifter bar or knife 19.

Each harness lever 21 has a pivotal movement on either one of its two fulcrs.

All of the above mentioned parts, except 55 the pattern indicator fingers 14, may be of

the construction, shown and described in U. S. Letters Patent, No. 884,613, above referred to.

I will now describe my improvements.

Secured to the dobby frame 2 and extending outwardly therefrom, is a stand 24, on which are pivotally mounted, on a stud 25 the hub of the upper knife or lifter bar 19, and also the hub, not shown, of the lower knife or lifter bar 20, see Figs. 3 and 4. 70 The lifter bars 19 and 20 have a simultaneous reciprocating movement in the same direction in a horizontal plane, in the slots 1' and 1'', see Fig. 1, in the frame 1, and also in the upper slot 2' and lower slot 80 not shown, in the frame 2.

To the opposite free end of the upper lifter bar 19 is pivotally attached, by a pin 26, a yoke shaped or bifurcated rod head 27, adjustable on the outer end of a rod 27, 85 see Fig. 1. The other end of the rod 27 is pivotally attached to a pin or stud 28, see Fig. 4, which is adjustably secured in an elongated slot 29' in the crank arm 29, on the upper end of a vertically extending rock 90 shaft 30, see Fig. 1, supported, and having a rocking or reciprocating rotary motion in bearings 31 secured to the rear dobby frame 1. On the lower end of the rock shaft 30 is a second crank arm 32, extending in this 95 instance in the same direction as the upper arm 29, and having an elongated slot therein to adjustably receive a stud 33, see Fig. 1, to which is pivotally attached one end of a rod 34. The other end of the rod 34 is 100 adjustably secured to the yoke or bifurcated rod head 35, which is pivotally connected by a pin 36, to the free end of the lower lifter bar or knife 20.

On the upper end of the rock shaft 30 is 105 fast a bevel pinion 37, see Fig. 1, which meshes with and is driven by a bevel gear segment 38, see Fig. 2, which has its hub 38' in this instance loosely mounted on a stud 39, secured to a lug or projection 1^a on the dobby frame 1. Extending out from the hub 38' of the bevel gear segment 38, is an arm 38'', which has an elongated slot 38''' to adjustably receive a stud 39, which is pivotally connected to the upper end of a rod 40, see Fig. 2. The lower end of the rod 40 is connected to some driven part of the loom, not shown, to have an intermittent movement communicated thereto at 110 regular intervals.

Through the vertical movement of the rod 40, and the movement of the arm 38'', and the bevel gear segment 38 and gear 37, a rocking movement is communicated to the vertically extending shaft 30, and through arm 29 and connector 27, to the upper lifter bar 19, and arm 32 and connector 34, to the lower lifter bar 20, at the rear of the dobby frame. A movement is communicated to said lifter bars to cause the same 120

to move simultaneously in or out in their guide slots, and turn on their pivot points on the opposite end of the dobby.

It will be understood that the details of 5 construction of my improvements may be varied if desired.

Having thus described my invention, what I claim as new and desire to secure by Letters Patent is:—

10 1. In a dobby, harness levers having a pivotal movement, hooks operatively connected thereto, a pair of lifter bars for operating said hooks, said bars pivotally connected at one end to a stationary part, and means, connected with a driven part of the 15 loom, to impart to the other ends of said lifter bars a back and forth movement about their pivotal points.

2. In a dobby, harness levers having a pivotal movement, hooks operatively connected thereto, a pair of lifter bars for operating said hooks, said bars pivotally connected at one end to a stationary part, and means, including a rocker shaft, and connections therefrom to the other ends of said 25 lifter bars, to impart a back and forth movement thereto about their pivotal points.

3. In a dobby, harness levers having a pivotal movement, hooks operatively connected thereto, a pair of lifter bars for operating said hooks, said bars pivotally connected at one end to a stationary part, and

means, connected to a driven part of the loom, to impart a simultaneous movement to the other ends of said lifter bars. 35

4. In a dobby, a harness lever having a pivotal movement, two hooks operatively connected with said harness lever, one pattern indicator lever to control the operation of both of said hooks, said indicator lever 40 having a separate pattern indicator surface for each of said hooks, one of said surfaces being placed in advance of the other, a pattern chain, having a series of indicators to coöperate with each of said surfaces, and 45 means to cause one of a series of said indicators to operate against one of said surfaces for one pick, and to cause one indicator of the other series to operate against the other indicator surface for the next pick 50 of the loom.

5. In a dobby, a harness lever having a pivotal movement on either of two fulcra, hooks operatively connected thereto, a pair of lifter bars for operating said hooks, said 55 bars pivotally connected at one end to a stationary part, and means, connected with a driven part of the loom, to impart to the other ends of said lifter bars a back and forth movement about their pivotal points. 60
